UNITED STATES PATENT OFFICE.

RULOFF R. BENNETT, OF NEW YORK, N. Y.

INVALID-COACH.

SPECIFICATION forming part of Letters Patent No. 623,591, dated April 25, 1899.

Application filed October 28, 1898, Serial No. 694,772. (No model.)

To all whom it may concern:

Be it known that I, RULOFF R. BENNETT, of New York, (Brooklyn,) in the county of Kings and State of New York, have invented 5 a new and useful Improvement in Invalid-Coachess; and I do hereby declare that the following is a full, clear, and exact description of the same, reference being had to the accompanying drawings, forming part of this 10 specification.

My invention relates to invalid-coaches—that is, coaches which are adapted to the carrying or transportation of sick persons, who can be carried thus from one place to another 15 without that unpleasant publicity which necessarily arises in the use of an ambulance. Coaches of this general character or for this purpose have heretofore been designed and used, an instance of which is to be seen in 20 the United States Letters Patent which were granted to myself April 24, 1894, No. 518,831. In all such coaches, however, as heretofore constructed and used there have been certain difficulties and defects, some of a serious 25 nature, which it is the object of my present invention to wholly overcome, and in the invalid-coach made the subject of my present application and which I have already reduced to practice and used with great suc- 30 cess the construction and mode of operation are radically different from those involved in any other invalid-coach heretofore made and have resulted in a coach which is much more desirable in all particulars, especially as to 35 those having reference to the safety and comfort of the invalid to be transported.

I propose by my present invention to provide for use an invalid-coach in the use of which the person to be carried may be placed 40 within the coach and removed therefrom with great ease and without the least inconveni- 45 ence or hurtful jar or movement to the patient, while at the same time during the carriage of the invalid the latter shall ride with the greatest possible degree of ease and com- 50 fort and may be attended or accompanied by two persons inside the coach, who will also be most comfortably accommodated.

To these main ends and objects my in- 55 vention may be said to consist in the novel structural features of an invalid-coach which will be found hereinafter fully described and

which will be most particularly pointed out in the claims of this specification.

To enable those skilled in the art to which my invention relates to make and use invalid-coaches embracing the latter, either in whole or in part, I will now proceed to more fully describe a coach made in accordance with said invention, (as I have so far practiced the latter,) referring by letters to the accompanying drawings, which form part of this specification and in which I have shown my invention carried out in that precise form as to details in which I have so far practiced it.

In the drawings, Figure 1 is a longitudinal vertical central section with the bed in its normal condition, but shown also in dotted lines as partially pulled out and resting on a supplemental supporting-roller which is one of the new features of my invention. In this figure the back of the coach is shown opened upwardly and outwardly and supported in its opened condition to permit the withdrawal and insertion of the removable bed or bed-frame on which the invalid is carried. Fig. 2 is a partial horizontal section taken at a plane indicated by the broken line *x x*, Fig. 1, and with the bed in its normal condition and the cushion-seats removed to better show certain parts to be described. Fig. 3 is a transverse vertical section at the broken line *y y*, Fig. 1, with the bed wholly within the coach, but in a central position widthwise of the latter to better illustrate certain devices and operations to be presently explained. Fig. 4 is a perspective view, looking at the foot, of the bed-frame with its air-bed and bed-covers detached or separated from the coach.

In the several figures the same part will be found always designated by the same letter of reference.

A is the body portion of the coach, of substantially the well-known approved form, mounted in about the usual manner on a suitable running-gear, which, however, is preferably of such detail construction as to render the carriage as easy and light running or as free from the effect to its occupant of any jar by passage over rough surfaces as is possible. The wheels are provided with rubber tires, the rear springs are made of the approved C-spring style, and all the bearings

of the running-gear which are capable of being rubbered are so made, for the purpose just above mentioned.

The rear end or back of the coach is comprised, mainly, of the portion B, which preferably has in it the usual back window for light and ventilation and that is hinged, as shown, at C, so that it may be opened outwardly and upwardly into the position shown in Fig. 1, in which opened condition it is securely held temporarily by hinged braces or stays F, which in closing down this back portion of the coach fold inwardly and out of the way very much after the fashion of the hinged stays of a buggy-top, and the lowermost part of the said hinged back piece B is provided near its sides with some suitable locking devices c, by means of which when the back of the coach shall have been closed it will be securely fastened, subject to be opened only by the use of a suitable key to operate said locking devices.

Each of the seats of the coach is provided, as shown, with a permanently-placed metallic track or rail o, on which rails is adapted to travel, within the coach-body and transversely thereof, the metallic carriage-frame J, which at its under side is provided with suitable peripherally-grooved track-rollers p, which travel on said transversely-arranged rails o, these parts being constructed and operating so that (when the seat-cushions to be occupied at one side of the invalid-bed shall have been removed) the said carriage-frame can be pushed along on its track or ways from one side of the coach-body to a position about central widthwise of said body, where further movement is prevented by certain stop devices in a manner and for a purpose to be presently explained.

As is clearly illustrated, the upper surface or portion of the transversely-movable carriage-frame J is provided with a series of revoluble rolls or antifriction-rollers j, on which rides or travels (as will be presently explained) the bed-frame I, which carries a rubber inflated or air bed H, on the outer end portion of which is placed an air-cushion a, which bed is provided, as usual, with a suitable sheet and coverings for the invalid to be transported. In the case shown this air-mattress and pillow are covered with a sheet, which is placed and held in position in a peculiar manner, which will be hereinafter explained, and with a covering-blanket or other additional covering b, such as may by preference be used for the comfort of the patient. This bed-frame I is preferably composed of a light strong rectangular wooden frame having a bottom formed of thin boards running longitudinally, so as to assure an easy running endwise of the bed-frame on the antifriction-rollers j of the carriage-frame J, and with a top surface composed, preferably, of canvas securely tacked to the frame, upon which rests in a removable manner the air-bed H. This air-mattress is, however, tem-

porarily secured in place on the bed-frame, so that there shall be no danger from its slipping about thereon while in use, by means of two broad flaps of canvas s, each of which is secured to the frame at one edge only, while the opposite or meeting edges of the two canvas flaps nearly meet and at their meeting edges are tied together at intervals by suitable tapes or strings, as clearly shown.

t t are broad bands or straps of suitable material, which have one end of each securely fastened to one of the sides of the bed-frame and are adapted to be drawn and held or tied over or around about the body of the person occupying the bed for the convenience and safety of such occupant in traveling.

As it is important that the sheet or cover of the air-bed H be so arranged and held in place as to avoid the possibility of its getting either partially displaced to the discomfort of the invalid or so as to possibly become entangled with some of the moving parts of the contrivance in either sliding the bed into the coach or removing it therefrom, I have devised the special arrangement shown, (see particularly Fig. 4,) in which the sheet or other covering of the bed is made of just the proper size to cover the person occupying the latter and not hang below the lowermost edge of the bed-frame I and so that by means of the earpieces or flap-like projections n and the tying of the sheet or other covering by the strings v, bound securely across the ends of the mattress, it is impossible for the covering to slip out of place, and thus cause either of the difficulties above mentioned.

As it is usual and necessary in the removal of a patient from his home bed to the bed to be carried into the coach, and vice versa, to use a canvas stretcher, which of course is carried in the coach, the stretcher-poles (each of which is, as usual, made in two parts adapted to be screwed together) are stored away in a most convenient and accessible manner by stacking up the four pieces against the front or riser of the back seat of the coach, as shown, one set of the ends of the stretcher-pole-pieces being held in place by a housing at one end of the seat-riser, while the opposite ends of the pole-pieces are securely held in place by a binder-strap i, preferably made of rubber and adapted also to perform another function, which will be presently described. This rubber strap i, one end of which is securely fastened at or near the base of the riser of the back seat, has its other end provided with a suitable ring or loop adapted to be caught onto or hitched to one or the other of two holder-buttons or hooks m n, the said strap when fastened, as shown in full lines at Fig. 3, to the hook or button m serving simply to retain in place the vertical stack of pole-pieces and when hitched to the button or hook n, as shown in dotted lines, performing the additional function of holding in place centrally, widthwise of the coach, the transversely-movable carriage-frame J,

said carriage-frame being held up against the stops *g g* (see Fig. 2) by said rubber strap to insure the retention of the said carriage-frame in this central position during either 5 the insertion or removal of the occupied bed-frame in the event of the coach happening to have the wheels at one side at a lower level than those occupied by the wheels at the other side.

10 *e e* are the usual rearwardly and upwardly projecting metallic arms of the back portion of the running-gear of the coach, which, however, I have made or formed at their ends with bearing-boxes which are slotted out at 15 their upper surfaces to permit the easy insertion and withdrawal of the journals of a supplemental roller *f*, which is temporarily used in a manner and for a purpose to be presently explained.

20 In the use or operation of my improved invalid-coach the bed-frame *I*, with its air-mattress, pillow, and bedclothes, having been removed from the coach (after having opened up the back of the latter, as shown in Fig. 1) 25 by first moving the transverse carriage *J* into the central position (seen at Fig. 3) and then drawing the bed-frame, with its accompanying parts, outwardly, as indicated by the dotted lines at Fig. 1, the said bed is taken to 30 any desired place from which the invalid is to be removed and after the person shall have been transported in the usual manner (by means of the canvas stretcher and its poles) and been properly placed upon the air-bed 35 the latter is then carried in the usual manner to the coach, and the foot of the bed-frame having been first placed on the supplemental roller *f* said bed-frame is gently pushed inwardly of the coach, rolling easily along 40 endwise on the said supplemental roller *f* and also upon the antifriction-rollers *j* of the transverse carriage *J*, until the bed-frame, with its occupant, shall have been pushed or placed wholly within the body of the coach. After 45 the performance of this operation the transverse carriage *J*, with the bed-frame resting thereon, is simply pushed easily widthwise of the carriage, its antifriction or grooved track-rollers *p* traveling on the transverse ways or 50 rails *o* until the bed, with its invalid, shall have been placed close against the right-hand side of the interior of the coach-body. Then the open back *b* having been closed and locked and the removable seat-cushions adapted to 55 be occupied by two persons, one on the back seat and the other on the front and both at one side of the bed, having been placed in position, one or two persons accompanying the invalid may occupy seats in the carriage (the 60 latter having had its door closed, as usual) and the invalid may be transported any distance with great comfort and perfect privacy.

To effectuate the removal of the invalid from the carriage, the reverse of the operations just described is of course performed—that is to say, after having discharged the accompanying passengers, removed the seat-

cushions occupied by them, and opened up outwardly the back portion *B* of the coach 70 the carriage-frame *J* is first pulled to its central position within the coach-body (see Fig. 2) and there secured in position against the stops *g g* by the elastic holder-strap *i*, if necessary, whereupon the attendants, taking hold of the head or pillow end of the sliding bed-frame *I*, pull the frame outwardly through the rear opening of the coach-body, having first, however, placed in position the removable supplemental roller *f*, the said bed-frame being easily drawn out without any jar or 80 commotion to the patient by rolling easily on the antifriction-rollers *j* (and also the roller *f*) until the foot end or portion of the bed-frame *I* shall be resting wholly upon the supplemental roller *f*, after which the attendants 85 can most conveniently lift and carry the bed-frame, with its bed and occupant, to any desired resting-place, at which it may be desired to apply the stretcher-poles to the canvas and carry the patient to his final destination. 90

Of course it is understood that when necessary to perform this final operation the four stretcher-pole pieces are easily obtained by unfastening the binder-strap *i*, removing the pole-pieces from their place of storage, properly screwing them together, and then inserting them in the side hems of the canvas stretcher, all in the usual or well-known manner. 95

It will be seen that by the construction herein shown and described not only is the removable bed-frame *I* placed at the lowest possible level, so as to be most readily inserted within and withdrawn from the coach-body by the attendants without jar or uncomfortable motion to the invalid, but that by the combination of the bed-frame *I* and transverse carriage *J*, the former being adapted to ride easily endwise on top of the latter and the latter being adapted to slide sidewise easily within the coach-body on the track-rails *o*, the necessary movements for the insertion of the bed within the coach when occupied by the invalid and the final movement of the bed to one side of the coach are all effectuated 100 easily by the attendants and without any jar to or any up or down movement of the invalid, and it will also be seen that by the utilization of the rearwardly-projecting arms *e* of the coach running-gear to support or journal 105 the removable supplemental roller *f* not only can the bed, with its occupant, be more easily and conveniently inserted within and withdrawn from the coach, but these operations can be performed without the slightest risk of 110 any jarring or shaking up of the patient, such as is very liable to occur where the attendants have got to get hold of and afford proper support to the inner or foot end of the traveling bed-frame at about the time of its losing the 115 support usually heretofore afforded by the hindmost one of the rollers *j* of the frame which supports the bed inside of the coach. 120

By having the air-bed *H* wholly and easily

removable from the bed-frame I (instead of having it permanently attached to it as heretofore) the air-bed, either for purpose of cleaning or repairing, may be removed by untying the binder or securing flaps *s s*, hereinbefore mentioned, and by the simple device shown and described the sheet and the bed-covering, while securely held in place against slipping during the placement on the bed or the removal from it of the invalid, are prevented from getting the lower edges displaced and lowered, so as to become entangled with or so as to interfere with either the sliding of the bed-frame on the rollered carriage-frame J or the movements of the carriage J.

Having now so fully described my improved invalid-coach that those skilled in the art can make and use coaches embodying either in whole or in part my alleged improvements, 20 what I claim as new, and desire to secure by Letters Patent, is—

1. In combination with a coach-body having its back portion adapted to be opened and closed, a carriage-frame arranged to travel laterally upon suitable ways on the carriage-seats; and a bed-frame which is adapted to be moved endwise on top of the said laterally-sliding carriage; all substantially as and for the purposes hereinbefore set forth.
2. In combination with the coach-body having a back which opens and closes, as speci-

fied; and the usual rearwardly and upwardly projecting devices *e, e*, of the running-gear, the bed-frame I arranged to be slid, or rolled into and withdrawn from the coach-body; and 35 a supplemental roller *f*, mounted in suitable bearing-boxes in the ends of the devices *e, e*; all substantially as and for the purposes set forth.

3. In an invalid-coach, a storage place, or 40 receptacle, for the four stretcher pole-pieces, in front of the riser of the rear seat, in combination with the retaining, or binder strap *i*; the combination being and operating as and for the purposes set forth.

4. In an invalid-coach, the combination, with the removable bed-frame I, of an air-bed which is separable from the said bed-frame; and the securing-flaps *s*, permanently attached at one set of their edges to the said bed-frame and provided with means by which their opposite edges may be temporarily secured together; whereby the said bed-securing flaps serve to securely, but temporarily, hold properly in place, on the bed-frame, the said 50 air-bed; all as hereinbefore set forth.

In witness whereof I have hereunto set my hand this 27th day of October, 1898.

RULOFF R. BENNETT.

In presence of—

DANIEL J. BYRNE,
WILLIAM P. RIDER.
